UNITED STATES PATENT OFFICE.

FRED F. BENSON, OF GALATA, MONTANA.

RAIL-JOINT.

1,295,678.

Specification of Letters Patent. Patented Feb. 25, 1919.

Application filed February 12, 1918. Serial No. 216,746.

To all whom it may concern:

Be it known that I, FRED F. BENSON, a citizen of the United States, residing at Galata, in the county of Toole and State of

5 Montana, have invented new and useful Improvements in Rail-Joints, of which the following is a specification.

This invention relates to means for connecting the alining ends of railway rails to 10 produce a perfect joint therebetween, so that danger of tilting, creeping, sinking or lateral movement between the rails will be effectively prevented, but wherein the limited longitudinal movement incident to the 15 expansion and contraction of the rails will not be impaired.

I accomplish the foregoing objects, and others which will appear as the nature of the invention is better understood by a construction, combination and operative arrangement of parts set forth in the following description and falling within the scope 20 of what is claimed.

In the drawings:—

25 Figure 1 is a perspective view of a rail joint in accordance with this invention.

Fig. 2 is a transverse sectional view through the same.

Fig. 3 is a perspective view of one of the 30 rail ends.

Fig. 4 is a perspective view of one of the tie plates.

In the drawings the rails are indicated by the numeral 5, and the ties on which the 35 rails rest, by the numeral 6.

The rails 5 are both of a similar construction, having their body portions formed in the usual manner to provide each with a head 7, a base 8 and a connecting web 9 between the head and base. Each of the rails, 40 at a suitable distance from the end thereof has welded thereto a longitudinally arranged outwardly extending bar 10. The bar 10 on one of the rails is, of course, disposed on the side thereof opposite that of the bar of the coacting rail, so that when the rails are assembled the bars will be received in the fishing spaces of the respective coacting rails.

45 As clearly shown by the drawings, each of the bars 10 is of a width or thickness equaling the distance between one face of the web of the rail and the upper edge of the base flange 8 opposite the said web, but 50 each of the bars or blocks 10 is reduced at

the upper and outer corner thereof, the inner walls 11 provided by the said reduced portion being arranged flush with the side of a head 7 of the rail.

The bars or blocks 10, at the portions 60 thereof welded to the rails, and also at the portions thereof extend outwardly of the rails are provided with transverse openings, certain of which being elongated, and certain of which also communicating with similar openings in the webs of the rails. These openings align when the rail ends are brought together and receive the usual bolts 12 which are provided with the securing nuts 13. In some instances, the nuts and 65 bolts may be dispensed with and the rail ends held together by lugs 14 formed adjacent the outer edges of tie plates 15. Two of these tie plates are employed, one for each of the rails, each of the tie plates resting on two of the ties 6, as illustrated in Fig. 1 of the drawings. The lugs 14 are beveled at the upper surfaces thereof and are provided with openings 16 through 70 which are passed the shanks of spikes 17 80 that enter the ties 6 and hold the lugs in contact with the outer and straight faces 18 of the bars or blocks 10.

By forming the bars or blocks 10, as disclosed by the drawings, each of the said 85 blocks is so shaped that the same may be received in the fishing space to either side of a rail and may be welded to either of the rails. The inner face of the block is not subjected to a welding heat, but the upper 90 and lower surfaces thereof are subjected to such a degree of heat. The thickness of the head and the foot or base of the rails is such that heat applied thereto will not penetrate entirely through the head and base to a degree which will affect the nature of the steel of which the rail is formed. The wedge 95 shape block, when forced in the fishing space of the rail only slightly contacts with the web thereof, so that no pressure need be applied against the opposite face of the web, such pressure being undesirable as the same would reduce the thickness of the web, and consequently two such rails could not 100 be brought to proper alinement. The straight shoulders 11 not projecting beyond the side of the rail head offer no obstruction to the flanges of wheels of rolling stock, and it is believed, from the foregoing description 105 when taken in connection with the draw- 110

ings that the simplicity and advantages of the improvement will be apparent without further detailed description.

It is to be understood, that while I have illustrated and described the bars or blocks 5 as being welded to the rails, such blocks 10 may be integrally formed with the rails in the construction of the said rails.

What is claimed as new is:

10 In combination with two abutting rails and ties on which the rails rest, of blocks in the opposite fishing spaces of the respective rails, welded thereto and projecting beyond the end thereof, said blocks being of a width

equaling the distance between the side of the 15 web and the edge of the base flange of the rails, each of said blocks having its upper and outer corner reduced providing an inner straight wall flush with the sides of the heads of the rails, tie plates beneath the 20 rails, lugs formed on said tie plates and engaging with the edges of the rails and the outer straight faces of the blocks, and securing means passing through said lugs and entering the ties. 25

In testimony whereof I affix my signature.

FRED F. BENSON.
